UNITED STATES PATENT OFFICE.

ROBERT J. STINE, OF EAGLE GROVE, IOWA.

HIDE-CLEANING TOOL.

1,383,873.

Application filed January 2, 1920. Serial No. 349,080.

Patented July 5, 1921.

Specification of Letters Patent.

To all whom it may concern:

Be it known that I, ROBERT J. STINE, a citizen of the United States, and a resident of Eagle Grove, in the county of Wright and

5 State of Iowa, have invented a certain new and useful Hide-Cleaning Tool, of which the following is specification.

The object of my invention is to provide a hide cleaning tool of simple, durable and inexpensive construction.

More particularly it is my object to provide such a tool comprising a plurality of spaced fingers peculiarly shaped and adapted for use in tearing the flesh stringing sinews 15 and the like from the inside of the hide, and to provide a cutting edge adjacent to said fingers for cutting the flesh cleanly, the parts being so arranged that the fingers will protect the hide and prevent any serious cutting 20 of the hide by the blade.

A further object is to provide in such a device, a handle member whereon the blade may be supported in such a way as to be reinforced and rigidly held.

25 With these and other objects in view my invention consists in the construction, arrangement and combination of the various parts of the device, whereby the objects contemplated are attained, as hereinafter more 30 fully set forth, pointed out in my claims, and illustrated in the accompanying drawings, in which:

Figure 1 is a side elevation of a hide cleaning tool embodying my invention.

35 Fig. 2 is a front elevation of the same.

Fig. 3 is a detail view partly in section of the tool; and

Fig. 4 is a front elevation of the cutting blade.

40 In the accompanying drawings I have used the reference numeral 10 to indicate generally a relatively rigid heavy plate. Formed at the lower edge of the plate 10, are spaced fingers 11, arranged in a series along the edge 45 of the plate, and inclined slightly rearwardly, as illustrated in Figs. 1 and 3.

Said fingers, while they do not have and should not have sharp edges are relatively thinner at their extreme edges, so as to form 50 what may be called blunt edges.

Extending rearwardly from the upper central portion of the plate 10, when the latter

is in substantially horizontal position, is a handle 12.

I am describing my tool as though it stood 55 in the position shown in Fig. 1.

At the upper edge of the plate 10 is a forwardly extending flange 13 from which extends a downwardly extending flange 14. It will be seen that there is formed a channel or 60 guide between the flanges 14 and the body of the plate 10.

I provide a cutting blade 15, the upper edge of which is received in said guide and snugly held therein. Extended through suitable openings in the plate 10, and the blade 15 which fits against the forward surface of said plate, is a screw 16, on the forward end of which is a nut 17 having a curled flange. At its lower edge the blade 15 is 70 provided with a sharp edge 18 which is spaced slightly forwardly from the fingers 11, and terminates short of the extreme lower end of said fingers, as clearly illustrated in Figs. 1 and 3.

75 The cleaning of hides is ordinarily a rather slow, unpleasant process.

With my improved tool I have found that I can clean a hide much faster than can be done with any of the tools now ordinarily 80 in use.

With the fingers 11 the flesh and the top stringy portion thereof may be quickly torn from the hide.

Where the fingers alone are used, the work 85 requires the exertion of much more energy and strength than where the blade 15 assists in cutting the flesh from the hide.

It is almost impossible to use a sharp knife 90 for this purpose, because a knife will result in cutting and injuring the hide, unless very carefully employed.

It will be noted that the blade 18 has its lower edge beveled on its forward surface as at 18°.

95 In tearing and cutting the flesh from the hide, the blade is pressed against the inner surface of the hide with the forward curved surfaces of the fingers pressing against the inside surface of the hide. The hide lying 100 substantially in the plane indicated by the dotted lines 20.

It will be seen that there is no chance for cutting deeply into the hide, and if the hide

should accidentally be cut at all by the blade 15, such blade will take off only a thin layer.

The fingers 11 are thin enough at their extreme edges to readily enter and tear the flesh, but are not sharp enough to cut through the flesh and injure the hide.

The parts of my improved hide cleaning tool are of simple and inexpensive construction. The blade may be readily taken out 10 and sharpened and replaced, and new blades can easily be substituted when desired.

The handle 12, and the plate 10, and fingers 11 are preferably made integral with each other, so as to support a very strong 15 tool.

The blade 15 is reinforced and is snugly held in position by being engaged in the guide formed by the flange 14.

Some changes may be made in the construction and arrangement of the parts of 20 my improved hide cleaning tool, without departing from the essential features and purposes of my invention, and it is my intention to cover by my claim any modified forms of

such structure or use of mechanical equivalents which may be reasonably included within its scope.

I claim as my invention:

In a hide cleaning tool, a handle having a plate at one end extending downwardly from the handle and provided at its lower edge with a series of fingers inclined downwardly and toward the handle end of the tool, said fingers having relatively thin but not sharp edges, said handle being provided at the upper part of said plate with a downwardly opening receiving channel, providing a receiving member for a blade, a blade having its upper edge received in said channel and projecting downwardly and terminating above said fingers, said blade being beveled at its lower edge on its side away from the fingers for providing a sharp edge adjacent to the fingers, a bolt extended through said plate and blade, and a nut on 45 said bolt.

Des Moines, Iowa, November 21, 1919.

ROBERT J. STINE.
